SHELF BRACKET

Joffre E. R. Hentzi, 355 Reservoir Road,
Kensington, Conn.

Filed Mar. 10, 1964, Ser. No. 78,948

Term of patent 14 years

(Cl. D33—3)

FIG. 3

FIG. 1 is a side elevational view of a shelf bracket embodying my new design;

FIG. 2 is a side elevational view of a shelf bracket embodying my design; and

FIG. 3 is a top plan view of the shelf bracket of my design.

The dominant features of the design reside in the portions shown in solid lines.

I claim:

The ornamental design for a shelf bracket, substantially as shown and described.
